UNITED STATES PATENT OFFICE

HERMANN DEUTSCH, OF CHICAGO, ILLINOIS

DRILLING JIG

Application filed December 31, 1927. Serial No. 243,999.

This invention relates to new and useful improvements in drilling machines and more particularly to means whereby to retain objects to be drilled, in their proper positions while being drilled. One of the objects of the present invention is the provision of a drilling device which can be minutely adjusted so that the devices to be drilled will be properly positioned with respect to the drill so that the drilling can be carried out to the proper proportion.

Another object of the invention is the provision of a device of the above character wherein the articles to be drilled are positioned in a movable carrier which may be manually or otherwise propelled to consecutively position the articles beneath the drill and dispense said articles after being drilled.

A further object of the invention is the provision of a device of the above character wherein the article carrier can be made in a single piece or in several pieces with each piece provided with an article receiving seat.

With the above and other objects in view the invention consists in the novel features of construction, the combination and arrangement of parts hereinafter more fully set forth, pointed out in the claim and shown in the accompanying drawings, in which

Figure 1 is a side elevation of a drilling device constructed in accordance with my invention.

Figure 2 is a top plan view.

Figure 3 is section on the line 3—3 of Figure 2.

Figure 4 is a top plan view with the rotatable carrier removed, illustrating the removable bottom plate.

Figure 5 is a section on the line 5—5 of Figure 4.

Figure 6 is a top plan view of a one piece carrier plate.

Figure 7 is an edge view of the plate illustrated in Figure 6.

Figure 8 is a detail plan view of the sectional article carrier.

Figure 9 is a section on the line 9—9 of Figure 8, and

Figure 10 is a sectional view on the line 10—10 of Figure 10.

In the accompanying drawings it will be noted that the entire device is supported upon a hollow base or standard 1, the lower end of which is formed with an annular flange 2, formed with openings 3 to receive any suitable type of fastening members to secure the base to a solid foundation. The upper end of the standard is also formed with an annular outstanding flange 4 which forms a suitable base or support for the other parts of the device.

Mounted upon the standard 1 and removably secured thereto by means of the screw bolts 5 is the bottom plate 6, which is formed with a groove 7, having its ends terminating into a transverse opening 8 through which the finished articles are dispensed. The perimeter of the bottom plate 6 is formed with an annular rib 9 forming a bearing surface upon which the circular carrier ring 10 is rotatably mounted. The lower edge of the ring 10 is provided with an annular rib 11, which projects inwardly and which engages beneath the rib 9 to retain the ring 10 against riding upwardly on the rib 9.

Threaded into the outer ring 10 and engaging the upper face of the rib 9 is a retaining ring 12 to which the carrier sectors 13 are secured by means of the set screws 14. The outer edge of each sector plate is formed with a lip 15 which projects over the ring 12 and is formed with an arcuate slot 16 to receive its respective set screw 14, so that each sector can be independently adjusted and retained in its proper adjusted position. The inner end of each sector is formed with a reduced part which is pivotally connected to the flanged head of a button like member 17, by means of the screw 18, said screw operating in an arcuate groove 19 and bearing against the sector 13 to retain the inner end of the sector in its proper adjusted position.

Each sector 13 is formed with an article receiving seat or opening 20, said seats or openings being of different shapes or of such shape as desired to accommodate articles of different shapes. These seats or openings are preferably positioned in line or above the groove 7, so that the waste material from the drilling will be received by them. In order

to properly position the articles to be drilled beneath the drill and retain them in this position, the ring 12 is formed with a circular series of conical openings 21, any one of which is adapted to receive the conical end 22 of the adjustable retaining member 23. The retaining member 23 is threaded and adjustably mounted in the supporting sleeve 24 on the upper end of the bracket 25. This bracket 25 is removably mounted upon the standard 1 by means of the screw bolts 26, the lower end of said bracket being seated in a suitable recess formed in one side of the standard. A removable screw bolt 26 is also extended through the bracket and engaged with the bottom plate 6.

The drill holder 27 is adjustably supported upon a bracket 28, which is removably attached to the standard 1 and upon which is mounted an adjustable standard or arm 29. The standard or arm is formed with a longitudinal slot 30 which receives the set screws 31 on the bracket 28, whereby the arm 29 can be raised or lowered and retained in its adjusted position. The holder 27 includes a threaded stem 32 having a hand wheel 33 at one end and the holder 27 at the other end. The stem 32 is threaded through a sleeve 34 and may be retained in an adjusted position by means of the set screw 35. The outer end of the retaining member 23 is formed with a hand wheel 36, whereby this member may be readily adjusted to project the end 22 into any one of the openings 21 or retract the same therefrom.

The solid or one piece article retaining plate 37 is formed with circumferentially spaced arcuate slots 38 to receive the set screws 14 to retain the plate 37 in various adjusted positions. The plate 37 is also formed upon its sloped peripheral edge with a series of graduations 39, which are used in connection with the indicator 40 when minute adjustments are required. The plate is also formed with article receiving seats or openings 41, which are so positioned that they will be disposed over the groove 7 when the plate 37 is in use.

From the above it will be apparent that in using the device as shown in Figure 2, the farthermost seat or opening 20 is ready to receive an article to be drilled while the article in the opening at the right has been moved under the drill and the article in the lowermost opening is about to be moved over the opening 8 to dispense the latter article. After one article has been drilled the member 22 is released and the ring 10 rotated to change the positions of the seats or openings 20, and as each article is correctly positioned beneath the drill the member 22 is moved into one of the openings 21 to retain the ring 10 and sectors against movement during the drilling operation. It will be apparent that the drill holder can be readily adjusted ver-

tically or laterally in accordance with the work and is so constructed that the same may be retained in various adjusted positions.

It will be noted that the waste material from the drilling will drop down into the groove 7 from where it may be readily cleaned out. It will be readily apparent that the sectors 13 may be readily adjusted through the medium of the set screws 14 and 18 so that drilling may be done in different parts of the articles held in the seats or openings 20. As stated heretofore, the one piece 37 can be used in place of the sectors 13 if so desired and minute adjustments can be obtained through the use of the graduations 39 and the indicator 40.

While I have shown and described the preferred form of my device it will be apparent that various changes and alterations may be carried out when putting the invention into practice without departing from the spirit of the invention or the scope of the appended claim.

I claim as my invention:

In a drilling jig a base member, a removable bottom plate secured to the base, said plate having a transverse opening, there being a circular groove in the upper face of the plate communicating with the opening, a rotatable member embracing the outer periphery of the plate, a plurality of sectors adjustably attached to the rotatable member and resting directly on the plate, said rotatable member having a plurality of openings in its outer surface, an adjustable member adapted to be projected into any one of said openings to retain said member against movement, and a drill holder adjustably carried by the standard and arranged above the path of the sectors.

In witness whereof I have hereunto set my hand this 7th day of December, A. D. 1927.

HERMANN DEUTSCH.
